Primary Examiner — George D. Kirschbaum*Assistant Examiner* — Lillian Windham(74) *Attorney, Agent, or Firm* — Paul Liu; Julie J. Muyco; Perkins Coie, LLP(57) **CLAIM**

The ornamental design for a lidar housing, as shown and described.

DESCRIPTION

FIG. 1 is a perspective view of a lidar housing showing the new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a perspective view of the lidar housing shown in use; and,

FIG. 9 is an elevation view of the lidar housing shown in use. The broken lines shown represent unclaimed elements and environment that form no part of the claimed design.

1 Claim, 5 Drawing Sheets(56)
